UNITED STATES PATENT OFFICE.

WILLIAM W. SLY, OF CLEVELAND, OHIO.

CRUSHER.

SPECIFICATION forming part of Letters Patent No. 514,097, dated February 6, 1894.

Application filed March 23, 1893. Serial No. 467,295. (No model.)

To all whom it may concern:

Be it known that I, WILLIAM W. SLY, a citizen of the United States, and a resident of Cleveland, in the county of Cuyahoga and State of Ohio, have invented certain new and useful Improvements in Crushers, of which the following is a specification.

This invention relates to machines for crushing ore, cinders, &c., and consists in the new construction and combination substantially as hereinafter described and pointed out in the claims.

In the accompanying drawings:—Figure 1 is a perspective view of my machine, having a head removed to show the interior construction. Fig. 2 is a longitudinal section of the machine. Fig. 3 is a cross section through middle of Fig. 2. Fig. 4 is a detached view of the rolling crusher. Fig. 5 is a view of the inside of one of the chambered heads.

A is a cylinder having an opening in one side for inserting the material to be crushed, closed by a strong door made as follows:

B is a strong frame riveted to the cylinder around the opening.

B² is a frame hinged at the upper side of the frame B.

B³ is a plate for covering the opening, its lower edge being inserted in a rabbet in the lower bar of frame B, the frame B² holding the cover down by the rod b, inserted through holes in the flanges of said frame B and lying over the lower part of frame B².

C C are chambered heads consisting of castings having hollow trunnions C', and are firmly riveted in the ends of the cylinder, and the cylinder is supported by these trunnions, in boxes C², mounted on a suitable framework which supports the entire machine. The chambers in the heads are preferably made square. One of the heads has four radial partitions C⁵, which divide the chambers into four compartments, centrally communicating with one another, and with the hollow trunnion. This chamber is closed by an inner plate C⁴ fastened by rivets, and it has openings C⁶ leading into the said compartments over inclines C⁶. Two of these inclines are so located in each of the four compartments of the chamber, that their inclined surfaces

lead to the said openings C⁵, and are designed for conducting the pieces of iron that may get into the chambered head back into the cylinder, while the dirt and lighter particles float off with the water. The opposite or 55 right hand head is not divided into compartments but is closed by a perforated lining plate inclosing the chamber. To the trunnion on this head is to be attached a hose or pipe for conveying water into the cylinder 60 through the said perforations. This is the inlet head, and the other the outlet head for the discharge of water and washing.

D is a rolling crusher, consisting of disks joined by wings radiating from the axis, and 65 forming angular troughs. This crusher is placed loosely in the cylinder, and rolls in the lower side thereof as the cylinder is revolved.

E is a ring gear bolted on to one end of the cylinder.

F is a shaft lying parallel with the cylinder, and has its bearing in the frame which supports said cylinder. G is a pinion on said shaft meshing with the said ring gear E, and on the end of the shaft is provided a driving 75 pulley H, by which power is applied for revolving the cylinder.

The operations of this machine are as follows:—It is intended principally for crushing cinders from cupolas, and collecting the iron 80 particles therefrom. The cinders are placed in the cylinder, and as the cylinder revolves the crusher rolls on the bottom and crushes the cinders under it. At the same time a large portion of cinders is carried over in 85 the troughs in the upper side of the crusher, and is dumped in front of it. They also serve to give additional weight to the crusher. Water is allowed to flow through the cylinder standing up about midway of the hollow 90 trunnions. The direction of the inclines is in opposition to the revolutions of the cylinder, that is they are not intended to act as scoops for catching the broken cinders, but will admit the ingress of water and the dirt 95 or lighter particles, and should any part of iron particles pass in, they being of greater specific gravity, would fall into the lower compartment in the chamber head, and as the compartments come up on a horizontal 100

line with the trunnions, the inclines and openings C⁵ in that compartment are in a position to discharge the iron back into the cylinder, the iron sliding on the inclines out of 5 the openings.

Having described my invention, I claim—

1. In a rotary crusher, a cylinder A chambered heads C C in said cylinder, hollow trunnions C' C' on said heads, supporting the 10 cylinder in bearings C² C² of the supporting frame; the rolling troughed crusher D, loosely placed in said cylinder; and means for rotating the cylinder, combined and operating substantially as and for the purpose set forth.
- 15 2. In a rotary crusher, a cylinder A having an opening in one side, a frame B surround-

ing said opening, frame B² hinged to said frame B, a plate B³ covering said opening; the rod b inserted in holes in flanges of frame B and lying over the frame B²; the chambered heads C C in the cylinder provided with hollow trunnions C' C', supporting the cylinder in bearings C² C² on the supporting frame, and the rolling troughed crusher D loosely placed in the cylinder; and means for rotating the cylinder, all constructed and combined to operate substantially as and for the purpose set forth. 20 25

WILLIAM W. SLY.
